MOLD FOR CHOPPED MEAT PRODUCT

Paul F. Ruhan, Eben St., Milford, Mass. 01757

Filed Feb. 3, 1972, Ser. No. 223,412

Term of patent 14 years

Int. Cl. D7—04

U.S. Cl. D7—43

FIG. 1 is a plan view of a mold for chopped meat product embodying my design.

FIG. 2 is a bottom plan view thereof.

FIG. 3 is an elevational view of the lower side thereof.

FIG. 4 is an elevational view of the upper side thereof.

FIG. 5 is an end elevational view thereof as seen from the left of FIG. 1.

FIG. 6 is an end elevational view thereof as seen from the right of FIG. 1.

FIG. 7 is a sectional view taken on line 7—7 of FIG. 1. I claim:

The ornamental design for a mold for chopped meat product, as shown.
